UNITED STATES PATENT OFFICE.

JULIUS W. LUNDSKOG, OF LYNN, MASSACHUSETTS, ASSIGNOR TO GENERAL ELECTRIC COMPANY, A CORPORATION OF NEW YORK.

COIL-FORMER.

No. 827,315.

Specification of Letters Patent.

Patented July 31, 1906.

Application filed December 29, 1903. Serial No. 186,949.

To all whom it may concern:

Be it known that I, JULIUS W. LUNDSKOG, a citizen of the United States, residing at Lynn, county of Essex, State of Massachusetts, have invented certain new and useful Improvements in Coil-Formers, of which the following is a specification.

The present invention relates to the winding of counterpart coils for the armatures of dynamo-electric machines, and more particularly to the devices upon which said coils are made.

The coil-formers heretofore in use have been objectionable on account of the large amount of skilled labor required to operate them, for when the insulated wire is wound into a completely-formed coil the wire has to be passed through numerous channels and recesses about projections and shoulders and held as each convolution is put in place by numerous retaining devices, and where the insulated wire is wound into an incompletely-formed coil which has to be shaped after removal from the form, while requiring less skill in winding, it has to be tied by numerous temporary binders to prevent the several convolutions from becoming displaced in the shaping operation.

The object of my invention is to provide a coil-former upon which the wire may be wound with a minimum expenditure of manual effort into an incompletely-shaped coil and by a simple manipulation of which the coil is given its completed shape.

In carrying out the invention I employ any approved form for winding a coil with a re-entrant side, such as the form shown in the patent to Webber, No. 561,636, granted June 9, 1896, and divide it into two parts, so that the part upon which the re-entrant side of the coil is supported is adapted to be moved relatively with respect to the other part carrying the outer or larger portion of the coil. The parts are provided with suitable hinge connections to prevent their displacement and with clamping devices to hold the offset bends of the coil in fixed relation during the shaping operation.

For a more complete understanding of my invention reference may be had to the following detailed description and the accompanying drawings, forming a part of this specification, in which

Figure 1 is a perspective of a coil-forming device embodying my invention with the coil 55 shown nearly wound. Fig. 2 is a top plan thereof with the clamping devices for the offset bends of the coil in their operative positions. Fig. 3 is a front elevation of the same. Fig. 4 is a central transverse section of the 60 coil-forming device, taken on line 4-4 of Fig. 2. Fig. 5 is an end elevation of the coil-forming device with the terraced inner part of the form and the clamping device indicated in various positions occupied by them during 65 the shaping of the coil. Fig. 6 is a sectional elevation of the front portion of the coil-forming device, showing the means for locking the members of the form together. Fig. 7 is an end elevation of the coil-forming device, 70 showing the several parts supporting the nearly-completed coil. Fig. 8 is a perspective of the wire-cutting means, and Fig. 9 is a perspective of a complete coil in an inverted position relatively to that in which it 75 was wound.

The form is supported upon a rectangular table A, having a central projection B from its under side adapted to be pivotally mounted upon a suitable pedestal for rotary movement about a vertical axis. To the upper surface of the table A is secured the main section of the form, which consists of a metallic plate 1, provided on its upper surface with a yoke-shaped frame 2, about the outer face of 80 which the longer part of the coil is formed. The ends of the yoke-shaped frame 2 are extended into projecting fingers 3, 3, which extend beyond the rear edge of the plate 1 and serve to hold the offset bends of the coil in 85 position during the winding operation. In the space within the frame 2 is disposed the movable section of the form, which consists of a plate 4, having a yoke-shaped projection 5 from its upper surface provided with steps 90 or terraces 6 for supporting the respective re-entrant convolutions of the coil. The plate 4 is connected by hinges 7, 7 to a shelf 8, which is in turn connected by hinges 9, 9 to the rear edge of the main plate 1. The front edge of 100 the movable section-plate 4 is provided with a lug 10, having an eye 11 and projecting downward into a channel 12 in the top of the table A, and co-operating with the lug 10 is a reciprocating lock-bolt 13, carried by a projection 14 from the under side of the main 105

plate 1, extending into the channel 12 in the table. The bolt is connected by a link 15 to a gage-arm 16, hinged to the main section-plate 1 at its front edge, so that when the arm 5 is lowered to its inoperative position the bolt will be moved into its locking position, as indicated in dotted lines, Fig. 6. The gage-arm 16 consists of a light rod provided at its outer end with a box 17 for receiving an end of the 10 coil-wire and is connected at its inner end to a hinged portion 18 of the main section-plate 1. The means for holding the gage-arm 16 up in operative position consists of a spring-catch 19 on the front edge of the table A. 15 The rear edge of the hinged portion 18 is cut away for a considerable portion of its length to form a channel 20, into which the starting end portion of the wire may be depressed below the plane of the coil. The 20 means for forcing the wire into the channel 20 consists of a bent finger 21, carried by the movable section-plate 4, which produces an offset in the wire, as shown at C, near the rear right-hand corner of the coil in Fig. 9. 25 The movable section-plate 4 is also provided in its front edge with projections 22, which are adapted to engage the starting end portion of the wire and clamp it upon the main section-plate 1 when the movable section-plate 4 is lowered into winding position. 30 Pivoted fingers 23 are located in notches 24 at the corners of the yoke-shaped frame 2 and serve to hold the several convolutions of the coil in place at these points during the 35 winding operation. The lower ends of the fingers 23 are provided with crank-arms 25, which are connected by a link 26, extending through the channel 12 and provided with a handle 27, whereby the fingers may be 40 caused to fold back into alinement with the shouldered frame 2 when it is desired to remove the complete coil from the form. 45 The means for confining the offset bends during the shaping or unfolding of the coil 50 consists of a flat clamping member 28, hinged at 29 29 to the rear edge of the shelf 8, so as to fold over upon the latter, being provided with notches 30 30 to clear the projecting fingers 3 3, and with shoulder-plates 55 31 31, which project upwardly in line of the axis of the hinges 7 and serve as abutments against which the movable section 4 contacts when moved outwardly beyond the vertical. A catch 32 is carried by the shelf 8, which is adapted to engage the front edge of the clamping member 28 and hold it in closed position. 60 The end of the table and main section-plate are provided with a slot 33, in which a lever 34 is fulcrumed. The lever is provided in one edge with a notch 35, which is adapted to coöperate with the corners of the slot 33 to sever the wire. The main and movable section-plates 1 and 4 are provided

in their front edges with recesses 36 37 to 65 permit retaining-clips 38 (shown in Fig. 9) being applied to the coil before removal from the form.

The coil is wound and shaped as follows: The parts of the form are brought into the 70 position shown in Figs. 1 and 6, with the gage-arm in elevated position. The starting end of the wire is placed in the box 17 and passed through the channel 20 beneath the bent finger 21. The movable section 4 75 is then forced down and the bolt 13 shot into locking position by the lowering of the gage-arm 16 to inoperative position. The wire is led to the left in front of the shouldered projection 2, around the left end under finger 3, 80 in front of the lowermost part of the terraced projection 5, around the right end of projection 2, under finger 3, and back to the position of the bent finger 21. This series of 85 steps is repeated for each succeeding convolution in the coil. The clamping member 28 is then folded over into the position indicated in Fig. 2, the clips 38 are slipped upon the coil, and the gage-arm 16 raised and the wire cut. The clamping member 28 is then 90 closed upon and locked to the shelf 8, and the movable section is raised by hand to the position x, Fig. 5, where it engages the abutting plates 31 and upon continued movement 95 forces the shelf 8 and clamping member 28 downward until the position y, Fig. 5, is reached, whereupon the clamping member 28 is unlatched and permitted to fall into the position indicated in Fig. 7. The coil is now 100 completely shaped and ready for removal from the form, which is done by throwing the handle 27 to the right to remove the fingers 23 from the path of the coil and then slipping the long side of the coil up by hand over the shouldered projection 2 and the short side 105 down off the terraces 6. The clips 38 will remain upon the coil until it is taped or applied to the armature.

I do not desire to restrict myself to the particular form of construction of parts herein described and shown, since it is apparent that they may be changed and modified without departing from my invention.

What I claim as new, and desire to secure by Letters Patent of the United States, is— 110
 1. A sectional coil-former upon which a coil in the form of a reentrant polygon may be wound, and provisions whereby one section and the portion of the coil carried thereby may be moved angularly relatively to the other section and the portion of the coil carried thereon.

2. A coil-former comprising a main section provided with a yoke-shaped frame for receiving the longer portion of the coil, and a movable section hinged to the main section and provided with a yoke-shaped frame for receiving the shorter portion of the coil.

3. A coil-former comprising two relatively revoluble sections for supporting the longer and shorter portions of the coil, and means for supporting the offset bends of the coil in 5 dependent of the positions of the said sections.

4. A coil-former comprising a main section and a movable section for supporting the opposite sides of the coil, a shelf hinged to both 10 of said sections, and a clamping member for retaining the offset bends of the coil hinged to said shelf.

5. A coil-former comprising a main section and a movable section for supporting the opposite sides of the coil, a shelf hinged to both 15 of said sections, and a clamping member for retaining the offset bends of the coil hinged to said shelf and provided with shouldered

projections for limiting the movement of the movable section in relation thereto. 20

6. A coil-former comprising a main and a revoluble section, and projections carried by said revoluble section and adapted to force the coil-wire into engagement with the main section when in folded position. 25

7. A coil-former provided with a yoke-shaped frame, pivoted fingers extending outward from said frame, and means for simultaneously rocking said fingers.

In witness whereof I have hereunto set my 30 hand this 24th day of December, 1903

JULIUS W. LUNDSKOG.
